UNITED STATES PATENT OFFICE.

GEORGE MINCHIN, OF SHAKESPEARE, ONTARIO, CANADA.

DESIGN FOR A SPOKE-SOCKET.

SPECIFICATION forming part of Design No. 14,558, dated January 22, 1884.

Application filed November 3, 1883. Term of patent 14 years.

To all whom it may concern:

Be it known that I, GEORGE MINCHIN, of Shakespeare, in the county of Perth, Province of Ontario, and Dominion of Canada, have invented and produced a new and original Design for Spoke-Sockets, of which the following is a full, clear, and exact description.

Reference is to be had to the accompanying drawings, forming a part of this specification, in which two perspective views of my newly-designed spoke-socket are shown.

The leading feature of my design consists of the T-shaped flanges formed upon the side edges of the outer end of the oval body of the socket.

A is the body of the socket, which is oval in its general contour, and B are the side flanges, only one of which is shown in the drawings. The flanges B are formed upon the side edges of the outer end of the body A, and

are extended laterally on each side of the socket, forming T-shaped flanges, as shown in the drawings. The edges of the flanges B are thinned or beveled, so as not to present an abrupt edge at the points where they met the felly, and so as to present an appearance of neatness and lightness, while giving an ornamental appearance to the wheel. In the end parts of the flanges B are formed holes. 30

I claim—

The design for a spoke-socket, herein shown and described, the same consisting of the oval body A, having upon the side edges of its outer end T-shaped flanges B, having a thinned or tapered outer edge, substantially as herein shown and described.

GEO. MINCHIN.
